Patented Jan. 19, 1864.

Inventor
John H. Aldrich

UNITED STATES PATENT OFFICE.

JOHN H. ALDRICH, OF HOLYOKE, MASSACHUSETTS.

IMPROVEMENT IN FLIERS FOR SPINNING-MACHINES.

Specification forming part of Letters Patent No. 41,268, dated January 19, 1864.

To all whom it may concern:

Be it known that I, JOHN H. ALDRICH, of Holyoke, in the county of Hampden and State of Massachusetts, have invented an Improved Flier for Slubbers and Speeders; and I do hereby declare that the following is a full, clear, and exact description of the same, reference being had to the accompanying drawings, making part of this specification, and to the letters of reference marked thereon.

Figure 1 is a plan of the flier with an empty bobbin. Fig. 2 is a plan of the same with the bobbin full. Fig. 3 is a front elevation of the flier. Fig. 4 is a side elevation of the same. Fig. 5 is a plan of the presser-arm and stop detached. Fig. 6 is an elevation of the same. Fig. 7 is a view of the pin or stem detached. Fig. 8 is a perspective view of the spring which connects the presser-arm with the pin and flier. Fig. 9 is a sectional plan of the flier of D. F. Smith, patented May 3, 1859. Fig. 10 is an elevation of the same. Fig. 13 is a detached view of Smith's arm and pin. Fig. 11 is a sectional plan, showing the presser-arm, &c., as frequently applied to the best speeders. Fig. 12 is a section of the same at A B.

In the flier (shown in Figs. 11 and 12) the stop or cam of the presser-arm is made so near the end or opening of the flier and the ears of the flier are so placed that the roving leaves the tube abruptly to wind upon the arm of the presser, and the stop or cam *a* is so far from the lower ear, *b*, of the flier that the leverage on the pin or stem causes them in time to work loose. In the improvement of D. F. Smith, patented May 3, 1859, Figs. 9, 10, and 13, the arm *c* and stem or pin *D* are made in one piece, and the cam or stop *e* put on the squared end of the stem, and a shoulder, *f*, is made on the stem to bear against the under side of the lower ear, *g*, of the flier; but the dirt and waste is liable to gather around the shoulder. This cam can only be altered one or more whole revolutions of the stem, for the purpose of adjusting the force of the spring to the required pressure on the bobbin. To obviate this difficulty, he makes two catches, *q r*, Fig. 13, so as to vary the strength of the spring by the equivalent of one-half a revolution; but this weakens the pin.

My invention consists in constructing a flier which admits of nicer adjustment, greater durability, and capable of a finish which leaves fewer places for dirt and waste to gather.

To enable others skilled in the art to make and use my invention, I will proceed to describe its construction and operation.

In my flier the tubular arm *i* of the flier runs a little below the cam or stop *j*, so as to lead the roving easily onto the presser-arm *O*, and leaves the parts as free as possible from anything to catch the dirt and fibers of cotton. The stop or cam *j* is brought close up to the bearing of the stem *k* in the lower ear, *h*, so that there is but little strain or leverage on the pin or stem, and consequently it is not liable to work loose or be bent. The spring *l* is attached in the usual way, one end being hooked to the pin *k* between the two ears *h* and *m*, and the other end to the flier, as will be readily seen.

By making the cam *j* and presser-arm *o* in one piece, Figs. 5 and 6, with the squared hole *n* to receive the squared end of the pin *k*, I obtain a nicer adjustment of the pressure on the bobbin as the roving is wound upon it, for, as will be seen, Fig. 5, the pin can be separated from the presser-arm *o*, turned one-fourth, one-half, or three-fourths, or one revolution, as required, to give more or less force to the spring; but in Smith's flier, Fig. 9, the cam being separate from the presser-arm *c* and pin *D*, must be turned a whole revolution to keep the relative positions of the arm and cam or stop *e*. If not turned a whole revolution, the cam will not allow the presser-arm to bear upon the bobbin.

I do not confine myself to the square for the end of the stem; but three, six, eight, or more sides can be substituted.

In other respects the flier is made in the usual way for first-class speeders.

I have described the two best fliers with which I am acquainted to contrast with mine. I have had my fliers tested long enough to prove their value. I know of no successful attempt having been made heretofore to obviate the above-described objections to speeder and slubber fliers.

Having thus described the construction and

operation of my invention, what I claim, and desire to secure by Letters Patent, is—

Constructing the cam or stop and presser-arm of slubber and speeder fliers in one piece, with the stop close to the under side of the lower ear of the flier, and having a hole to receive the squared end of the pin, thus pre-

venting too great strain upon the pin and admitting of greater nicety of adjustment, as herein described.

JOHN H. ALDRICH.
